MACHINE GUN

Robert J. Rickenbacher, Columbus, Ohio, assignor
to The Kilgore Mfg. Company, Westerville,
Ohio, a corporation of Ohio

Application November 19, 1934, Serial No. 753,561

7 Claims. (CL 42—57)

It is the object of this invention to provide a toy machine gun pistol with the handle permanently attached for operating the gun, but so arranged that it can be moved from an operative position, where it can be easily moved by hand to an inoperative position closely adjacent the side of the pistol.

It is a further object to provide such a pistol in which the handle is yieldingly held in either the operative or the inoperative position.

It is an object of the invention to provide a storage space for the ammunition strip which is readily accessible for loading, and which is located remote from the firing mechanism.

It is a further object of the invention to provide a toy pistol with timed feeding and firing mechanism, preferably utilizing a perforated strip of ammunition without a trigger but with an operating handle so that it may be fired rapidly or continuously as in a machine gun.

These and other features will appear from the following description taken in connection with the drawings.

Referring to the drawings:

Figure 1 is a side elevation of the pistol taken from the righthand side, showing the operating handle in inoperative position.

Figure 2 is a front elevation of the pistol as shown in Figure 1.

Figure 3 is a top plan view of the pistol as shown in Figure 1.

Figure 4 is a top plan view of the pistol with the barrel broken away, showing the handle in operative position.

Figure 5 is an elevation of the lefthand side of the pistol.

Figure 6 is an elevation of the righthand side of the pistol, showing the handle in operative position.

Figure 7 is a front elevation of the pistol as shown in Figure 6.

Figure 8 shows part of the strip of ammunition.

Figure 9 shows the lefthand side of the pistol with the closure for the ammunition chamber open.

Figure 10 is a side elevation of the inside of the lefthand side of the pistol.

Figure 11 is a horizontal section substantially on the line 11—11 of Figure 9, showing the handle in inoperative position.

Figure 12 is an inside view of the righthand side of the pistol, showing the operating parts supported thereby.

Figure 13 is a section substantially on the line 13—13 of Figure 9.

Figure 14 is a section on the line 14—14 of Figure 9, showing the handle in an inoperative position and in a position to be moved so that it will lie substantially parallel with one side of the pistol.

Figure 15 is a view similar to Figure 12 but showing the hammer in a position to be released for striking the ammunition on the anvil.

Figure 16 is a section showing the relation between the handle and the rotary anvil, with the anvil in inoperative position but in a position so it may be readily moved to operative position.

Figure 17 is a view similar to Figure 16 but showing the handle fully in its operative position.

Figure 18 is a view similar to Figure 17 except that the handle is in the reverse position to that shown in Figure 17.

Figure 19 is a view showing the hub end of the rotatable anvil.

Figure 20 is a view showing the end of the rotatable anvil opposite the hub end.

The pistol has an outer casing formed of two sides, a lefthand side 1 and a righthand side 2, joined together by means of bolts or screws 3. The numeral 4 represents the butt or grip end of the pistol, while the numeral 5 represents the barrel.

The part or side 2 has therein one-half 6 of an ammunition chamber, while the other half is formed in a removable and pivoted part 7. This part 7 is pivoted to the two sides by means of a lug 8, which has a hole therein through which one of the bolts or screws 3 passes. This part 7 has extending laterally therefrom a projection 7a, which is engaged by the finger of the operator so that the part is held in closed position but may be readily removed for opening the chamber when the finger is removed from the opening provided therefor between the ammunition chamber and the grip or butt of the pistol.

In the ammunition chamber is a pin or projection 9 adapted to support a roll 10 of ammunition formed of a strip 11. On the inside of the casing and on the side 1 is a boss 12, which has extending therethrough a hole 13 for receiving a plunger 14. This plunger has on its outer end a limiting shoulder 15 and on its inner end a head 16 adapted to be engaged by one end of a coil spring 17 which surrounds the plunger and has its other end in engagement with the boss 12 for causing the plunger to move inwardly. Within the casing and between the boss 12 and

the righthand side of the casing is a rotary anvil 18 which has adjacent the boss a cone-shaped cavity 19 into which the boss partly projects. On the end of the anvil remote from the boss 12 is a hub 20, which projects into and through a hole 21 provided therefor in the righthand side of the pistol casing. The cone-shaped cavity terminates in a hole which extends centrally through the hub, which has extending from the hole a pair of radially disposed notches 22 adapted to receive a crank member 23 for rotating the anvil. This crank has on one end a handle 23a, while its other end is slightly bent at 24 to form a neck part which projects through the hole in 15 the hub into the cone-shaped cavity.

This neck part has on its end a ball 25 which is sufficiently large to prevent the handle becoming displaced by the ball passing through the hole in the hub. This ball has on one side there- 20 of a cam member 26. This ball and cam member are in engagement with the head on the inner end of the plunger 14, and the spring 17 tends 25 to hold the head in engagement with the ball 25 and the cam member 26. The handle has there- 25 on a lug 27 adapted to fit in either one of the notches 22 so that the anvil may be rotated by a rotation of the crank.

Figures 17 and 18 show the crank in a position 30 with the lug in one of the notches 22 so that 30 a rotation of the crank will rotate the anvil and feed the ammunition strip. When the crank is in this position the handle 23a is in the position shown in Figure 4. The crank may be swung so 35 that the lug 27 is withdrawn from the notch 22, and when so withdrawn the crank may assume a position substantially parallel with the side of the pistol, as shown in Figures 1, 2, and 3. When the crank is in this position the pistol may be carried in the pocket, or it may be placed in 40 a carton or case provided therefor.

The spring 17 forcing the head 16 against the cam member 26 tends to hold the crank in in- 45 operative position. When the crank is in opera- tive position the head 16, acted upon by the spring 17 engaging the ball, tends to hold the crank in operative position for rotating the anvil.

The anvil is in the form of a hollow drum and has on its periphery a plurality of radially ex- 50 tending projections 28 adapted to extend through holes 29 in the strip of ammunition 11. These holes 29 for receiving the feeding projections alternate with ammunition charges 30. The rotation of the anvil will cause the ammunition strip to advance, due to the projections extending 55 through the holes 29. As the strip of ammunition advances and is fired the used end will pass out through an outlet 31 provided therefor in the top of the pistol.

For the purpose of firing the ammunition a 60 hammer 32 is provided which is pivotally mounted upon a pivot member 33 in the form of a pin extending from the inside of the righthand side of the pistol casing. For the purpose of urging the head of the hammer toward the anvil a spring 65 34 is provided. This spring intermediate its ends is coiled and fits over the pivot of the hammer while one end is engaged by a post 35 and its other end fits into a pocket 36 provided therefor in the hammer. This spring and its relation to 70 the hammer are shown in Figure 12.

The end of the hammer remote from its pivot is provided with a head 37 adapted to engage the ammunition for firing. Adjacent the head and between the head and the pivot of the hammer 75 is a lifter arm 38 adapted to be engaged by the

projections 28 on the rotatable anvil for the purpose of withdrawing the hammer so that under the influence of the spring 34 it may again engage the anvil to fire the ammunition after the projection has passed beyond the lifter arm in the 5 course of rotation.

For the purpose of stripping the used end of the strip of ammunition from the rotatable anvil a spring 39 is provided, which is supported at one end in the barrel of the pistol by means of sup- 10 porting projections or lugs 40, and has on its other end a stripper 41 closely engaging the periphery of the anvil and provided with a notch 42 through which the projections pass during the rotation of the anvil. The pistol is provided with a finger 15 guard 43 located between the ammunition chamber and the butt or grip of the pistol.

The present pistol is a machine gun type of pistol, in which the ammunition is fed from a roll by means of a rotating anvil having projections 20 thereon adapted to pass through openings in the strip of ammunition for feeding purposes. The projections on the rotatable anvil serve not only as instrumentalities for feeding the strip of am- munition but they serve to operate the hammer 25 by engaging the lifter arm 38.

When this arm is engaged by any one of the projections 28 the hammer head is withdrawn from the anvil and at the same time the strip of ammunition is fed forwardly so one of the charges 30 30 is brought forward to be engaged by the head of the hammer after the projection passes beyond the lifter arm so that the hammer will be brought into impact with the ammunition strip, due to the action of the spring 34.

The ammunition chamber, as will be observed from an examination of Figures 9 and 12, is located on the side of the anvil opposite that part on which the ammunition is fired. This pro- 40 tects the ammunition and also makes it possible to provide an ammunition chamber that is ac- cessible and readily closed by means of the mem- ber 7 pivotally connected to the barrel end of the pistol. This member 7 also has a projection adapted to be engaged by the finger of the opera- 45 tor so that the member 7 will be held in a position to close the ammunition chamber and protect the ammunition located therein.

It will be understood that I desire to comprehend within my invention such modifications as 50 come within the scope of my claims and my invention.

Having thus fully described my invention, what 55 I claim as new and desire to secure by Letters Patent, is:

1. In a toy pistol, a pair of side members, one side member having a hole therein, a rotary anvil having a hub thereon projecting into the hole, said anvil and hub having an axial cavity therein, a spring-pressed plunger slidably supported by 60 the other side member and projecting into the cavity, a handle member having a ball on one end fitting in said cavity and engaged by the plunger, and cooperating means on the hub and the handle member whereby the anvil may be rotated by the 65 handle member.

2. In a toy pistol, a pair of side members, one side member having a hole therein, a rotary anvil having a hub thereon projecting into the hole, said anvil and hub having an axial cavity therein, 70 a spring-pressed plunger slidably supported by the other side member and projecting into the cavity, a handle member having a ball on one end fitting in said cavity and engaged by the plunger, and cooperating means on the hub and the handle 75

member whereby the anvil may be rotated by the handle member, said ball having a cam thereon engaged by the plunger to hold the handle adjacent one side member.

5. 3. In a toy pistol, a pair of side members, one side member having a hole therein, a rotary anvil having a hub thereon projecting into the hole, said anvil and hub having an axial cavity therein, a spring-pressed plunger slidably supported by the other side member and projecting into the cavity, a handle member having a ball on one end fitting in said cavity and engaged by the plunger, and cooperating means on the hub and the handle member whereby the anvil may be rotated by the handle member, said cooperating means comprising a lug on the handle member fitting in a notch in the hub.
10. 4. In a toy pistol, a pair of side members, one side member having a hole therein, a rotary anvil having a hub thereon projecting into the hole, said anvil and hub having an axial cavity therein, a spring-pressed plunger slidably supported by the other side member and projecting into the cavity, a handle member having a ball on one end fitting in said cavity and engaged by the plunger, and cooperating means on the hub and the handle member whereby the anvil may be rotated by the handle member, said ball having a cam thereon engaged by the plunger to hold the handle adjacent one side member, said cooperating means comprising a lug on the handle member fitting in a notch in the hub.
15. 5. In a toy pistol, a pair of side members, one of said side members having a hole therein and the other side member having a boss extending toward the hole, a rotary anvil having on one end a hub projecting through the hole and a central cavity into which the boss projects, a spring-operated plunger on the boss in the cavity, a handle having one end loosely mounted in the cavity and engaged by the plunger, and means on the handle engaging the hub whereby the handle will rotate the anvil.
20. 6. In a toy pistol, a pair of side members, one of said side members having a hole therein and the other side member having a boss extending toward the hole, a rotary anvil having on one end a hub projecting through the hole and a central cavity into which the boss projects, a spring-operated plunger on the boss in the cavity, a handle having one end loosely mounted in the cavity and engaged by the plunger, and means on the handle engaging the hub whereby the handle will rotate the anvil, said means comprising a lug fitting in a notch in the hub.
25. 7. A new article of manufacture for use as an operative mechanism for a toy pistol comprising a rotating member having a transverse slot in its face and a ball-receiving socket, an operating handle having a ball on one end thereof mounted in said socket, means for yieldingly holding said ball in said socket, and a shoulder on said handle adjacent said ball adapted to engage in one of the slots on the face of the rotating member, the other of the slots being adapted to receive the handle in its inoperative position when the shoulder thereon is out of the other slot.

ROBERT J. RICKENBACHER.
